DISPENSING BOX

Charles Sam Adorney, Forest Hills, and Lester Dean Gill, Brooklyn, N. Y., and John Gibson McIlvain, Jr., Downingtown, Pa., assignors to Oakite Products, Inc., New York, N. Y., a corporation

Application January 25, 1951, Serial No. 207,754

3 Claims. (Cl. 229—17)

1
The invention relates to boxes formed of paper-board or the like, and more especially to dispensing boxes for fluent materials such as granular cleaning powder.

Various types of boxes have been proposed in which the user merely presses on some parts of the box to create a dispensing opening which will be closed when this pressure is released. For various reasons, none of these has been entirely satisfactory.

The primary object of the present invention is to provide a satisfactory and workable dispensing box of this type.

Another object of the invention is to provide a box of this type which is inexpensive and simple.

Still another object of the invention is to provide a box of this type which can be filled and closed by standard machinery.

A further object of the invention is to provide a box of this type which maintains the material tightly sealed within it during shipping and other handling, but which is very easily opened by the user when material is to be dispensed from it.

Still a further object of the invention is to provide a box of this type which is purely rectangular, so that large numbers of the boxes can be packed together in cartons or stocked on store shelves.

An additional object of the invention is to provide a box of this type, in which a quadrilateral opening is formed along the top of one of the side panels, with means which ensure the proper folding of the parts to produce such an opening.

Further objects and advantages of the invention will appear more fully from the following description, especially when taken in conjunction with the accompanying drawings which a part thereof.

In the drawings:

Fig. 1 shows the top part of a box blank for assembly into a box embodying the invention;

Fig. 2 is a perspective view of the dispensing corner portion of a finished box;

Fig. 3 is a similar view of the box in use; and

Figs. 4 and 5 are cross-sections on the lines 4—4 and 5—5 respectively of Fig. 2.

The box according to the invention includes front and back panels 1, 2 and side panels 4, 6, the latter cooperating with glue lap 8 to complete the box. Panels 2 and 1 have connected with them flaps 10 and 12, while side panels 4 and 6 have flaps 14 and 16 respectively. The

panels also have bottom flaps of any suitable type.

The top part of side panel 4 has a pair of lines of weakening or bending 18, preferably scored lines, these lines diverging downwardly from their meeting point in the center of panel 4 to the edges of the panel. From the meeting point of lines 18 a line of weakening 20, preferably also a scored line, extends vertically upward to the top edge of the side panel 4. The line of division or folding 22 between this side panel and flap 14 is severely weakened, preferably for example by a line of spaced slits which extend entirely or almost entirely through the board. Between the other panels and their flaps, on the other hand, preferably only the normal crease lines for bending are provided.

Flap 14 has a line of weakening, preferably formed by a longitudinally extending central score 24 aligned with, and preferably as an extension of, score 20. The area 26 on both sides of this line, at least for most of its length, is provided with a coat of ink or paint of the type used in printing to which the adhesive which is used in sealing the box will not adhere.

Flap 10 has a line of weakening 28, preferably a slit, extending centrally longitudinally thereof, and surrounded by an area 30 of a similar ink or paint. Flap 12 has a similarly located, and preferably somewhat longer, line of weakening 32 preferably formed by spaced slits going largely or entirely through the material. Both lines 28 and 32 preferably terminate a short distance from the ends of flaps 10 and 12.

Indications, as at 34, may be provided on the front and rear panels 1, 2 adjacent the top of the box, to show where pressure is to be applied to open the box. Of course, if a wrapper is to be applied to the box, these would be omitted from the box and would appear on the wrapper instead.

In assembling the box, the front and rear panels 1, 2 are folded into parallel position and glue lap 8 is glued to the inside of side panel 6. The bottom of the box is formed in the usual way. In closing the top of the box, flaps 14 and 16 are folded down. Flap 10 is now folded down and adhesively secured to flaps 14 and 16 (except in the area 26) and flap 12 is folded down and adhesively secured to flap 10 (except in the area 30).

When the material is to be used, the user presses at points 34 on the front and rear panels. This pressure causes the top of the box and the top of side panel 4 to fold along their lines of weakening, so that the perforated line 22 breaks

to form a quadrilateral opening 36 as shown in Fig. 3. The material may then be poured from the spout so formed.

It has been found that the provision of lines of weakening extending longitudinally of the top from a point at or near the upper edge of the side panel assists in the formation of a satisfactory spout. The use of lines of weakening, as at 24, 28, 32 in the flaps makes the breaking of line 22 easier and more accurate.

The proper operation is also assured by the lack of adhesion at surfaces 26, 30, which may be accomplished either by omitting adhesive over these areas or by printing them with a material which resists adhesion. Printing these areas with ordinary ink or paint such as used in printing is sufficient if a glue of sufficiently low viscosity is used and applied lightly on the flaps, as is usual in standard package filling machines. The application of varnish to these areas makes non-adhesion even more certain. Fig. 5 has been marked to indicate this condition, the areas of adhesion being indicated by crossed lines while the areas of non-adhesion are shown by small circles, along the meeting surfaces of the flaps.

The package so formed can be handled and shipped under normal conditions without danger of breaking open, yet it can be readily opened by the purchaser when the material is to be used.

While specific types of lines of weakening at 30 different points have been described herein, it is to be understood that within the broader aspects of the invention other types might be used at such points, including scores, cut scores, perforations or cuts.

While we have described herein some embodiments of our invention, we wish it to be understood that we do not intend to limit ourselves thereby except within the scope of the claims hereto or hereinafter appended.

We claim:

1. A dispensing package comprising a box having front, back and side panels and having flaps at one end of each of the front and back panels and at least one of the side panels folded down to close the end of the box, a first line of severe weakening forming a tear line between the side panel and its flap, a second line of weakening extending longitudinally of the side panel from about the center of the first line, third and fourth lines of weakening extending angularly from the end of the second line remote from the first line

to points adjacent the edges of the side panel, a fifth line of weakening in the side panel flap extending substantially in alignment with the second line, and sixth and seventh lines of weakening in the front and back panel flaps aligned with said fifth line, the side panel flap underlying the front and back panel flaps, the line of weakening in the lower of the front and back panel flaps constituting a slit, said sixth and seventh lines terminating a short distance away from said tear line.

2. In a package as claimed in claim 1, said flaps being adhesively secured over substantial parts of their areas but being free of one another adjacent the lines of weakening therein.

3. A dispensing package comprising a box having front, back and side panels and having flaps at one end of each of the front and back panels and at least one of the side panels folded down to close the end of the box, a first line of severe weakening forming a tear line between the side panel and its flap, a second line of weakening extending longitudinally of the side panel from about the center of the first line, third and fourth lines of weakening extending angularly from the end of the second line remote from the first line to points adjacent the edges of the side panel, a fifth line of weakening in the side panel flap extending substantially in alignment with the second line, and sixth and seventh lines of weakening in the front and back panel flaps aligned with said fifth line, the side panel flap underlying the front and back panel flaps, the line of weakening in the lower of the front and back panel flaps constituting a slit, said flaps being adhesively secured over substantial parts of their areas but being free of one another adjacent the lines of weakening therein.

CHARLES SAM ADORNEY.
